Specification for Design.

Patented May 17, 1921.

Application filed October 12, 1920. Serial No. 416,561. Term of patent 7 years.

To all whom it may concern:

Be it known that we, GEORGE V. STRAHAN and FREDERICK W. MATHIEU, citizens of the United States of America, and residents, respectively, of the city of Newark, county of Essex, and State of New Jersey, and of the borough of Manhattan, city, county, and State of New York, have invented a new, original, and ornamental Design for a Ceiling-Plate for a Lighting-Fixture, of which the following is a specification, reference being had to the accompanying drawings, forming part thereof.

Figure 1 is a plan view, and Fig. 2 is a section on the line 2—2 of Fig. 1, of a ceiling plate for a lighting fixture, showing our new design. In Fig. 1 the surface ornamentation is shown only in one quadrant of the plate; it being understood that this surface ornamentation is repeated over the entire surface of the plate.

We claim:

The ornamental design for a ceiling plate for a lighting fixture, as shown.

GEORGE V. STRAHAN.
